CARL SILBERSTEIN, OF BERKELEY, CALIFORNIA.

COIN-WRAPPER.

1,155,624.

Specification of Letters Patent.

Patented Oct. 5, 1915.

Application filed April 1, 1914, Serial No. 828,741. Renewed September 1, 1915. Serial No. 48,577.

To all whom it may concern:

Be it known that I, CARL SILBERSTEIN, a citizen of the United States, residing at Berkeley, in the county of Alameda and State of California, have invented new and useful Improvements in Coin-Wrappers, of which the following is a specification.

The object of the present invention is to provide means for rapidly and conveniently 10 inclosing in a package a pile of coins of equal value, said means being so constructed that it will indicate whether or not the correct number of coins have been so inclosed.

In the accompanying drawing, Figure 1 15 is a broken plan view of my improved wrapper; Fig. 2 is a perspective view of the same filled with coins and partly folded to form a package; Fig. 3 is a perspective view of the completed package.

20 Referring to the drawing, my improved wrapper comprises a substantially rectangular sheet 1 of paper one end 2 of which is folded over a narrow rectangular strip 3 of thin brass or other suitable metal. Said 25 strip 5 is formed at its ends with extensions 4, which in form are almost complete circles, being connected to the main portion of the strip by narrow necks 5, and the sheet 1 and folded-over portion 2 of the paper are 30 formed with similar extensions 7, 8, respectively underlying and overlying the circular extensions 4. The strips 2 and 3 are secured by any suitable adhesive to the paper 1, and the extensions 4, 7 and 8 are similarly 35 secured by adhesive to one another.

To use the wrapper the extensions are first bent up so as to stand vertically above the wrapper and strips 2, 3, being then substantially in line with the edges of the narrow 40 end of the wrapper projecting a short distance beyond the necks 5. The narrow extending end of the wrapper is then bent into a cylindrical form, so that its ends lie closely in contact with the circular edges of the extensions. This portion of the wrapper then 45 forms a cylindrical receptacle closed at the ends and partly closed on one side and open at the top and on the other side. The coins are now inserted in said receptacle in a horizontally extending series, and it may be at 50 once determined by the closeness of the fit of said coins in said receptacle, whether the proper number of coins have been inserted, as for instance, twenty or forty nickels, ten 55 or twenty dimes, and so on. When the receptacle is properly filled with coins, the re-

ceptacle and the coins therewithin are rolled toward the other end of the wrapper, and the ends of the wrapper are then folded in over the extensions or ends of the receptacle, 60 as is usual in forming coin packages.

The novelty and utility of the device consist in the provision of the thin metal strip 3 attached to the sheet of paper. This metal is sufficiently pliable so that it can be easily 65 bent or curved into a cylindrical form to form a side of the receptacle and its ends can be readily bent up to form the ends of the receptacle, and yet sufficiently stiff that said side and ends firmly retain their positions 70 while the receptacle is being filled with coins. There is thus provided a receptacle of inviolable size and form for receiving the coins, thus insuring that the proper number of coins are placed in the receptacle when filling it, and greatly facilitating the operation 75 of assembling the coins in packages.

I am aware that it has been proposed to provide a wrapper entirely composed of paper of a form resembling in general that 80 disclosed herein, but the paper wrapper does not form walls which are sufficiently rigid to insure the absolute uniformity at all times in size of the receptacle. I am also aware that it has been proposed to use a strip of 85 metal as a bond for binding the coins in the wrapper. Such use I do not claim. I am also aware that it has been proposed to form a receptacle the ends of which are made of wood. The objection to this form of wrapper is that the wrappers cannot be laid flat 90 when opened out, and cannot be stacked up in a small compass.

I claim:—

1. A coin wrapper comprising a sheet of 95 paper reduced in width at one end, a strip of thin sheet material of greater strength than the paper extending transversely across the paper at said end, said paper being folded over said strip, adhesive securing said strip 100 and folded portion to the sheet of paper, said strip having at each end substantially circular extensions, and the paper and folded portion having similar extensions registering with the extensions of the strip, and adhesive securing said paper, strip and folded portions, as likewise the extensions, to one 105 another.

2. A coin wrapper comprising a sheet of paper one terminal portion of which is 110 formed on opposite sides with approximately circular portions, and a strip of thin

sheet material of greater strength than the paper extending across said terminal portion of the paper and having approximately circular portions exactly overlying the circular portions of the paper, and adhesive securing said strip to the paper and the circular portions to one another.

In testimony whereof I have hereunto set my hand in the presence of two subscribing witnesses.

CARL SILBERSTEIN.
